CORE FORM FOR CASTING CONCRETE
TUBES

Arthur E. Troiel, Berkeley, Calif.

Application January 13, 1943, Serial No. 472,283

3 Claims. (Cl. 25—128)

1

The present invention relates to forms for casting concrete tubes, and particularly to forms for making pile caps.

Pile caps, sometimes referred to as pile jackets, are usually square tubular reinforced concrete castings which are placed over the upper ends of concrete piles after they have been driven, the caps being cemented in place. The upper ends of the caps support the floor or wharf for which the piles serve as a foundation and may be fixed at a uniform height, though the piles themselves are driven to different depths.

Such pile caps are preferably cast with rounded corners to prevent chipping away of sharp edges. They are usually approximately two feet in breadth and may be used in any desired lengths, but are seldom over eight feet long. Because of their size and shape, it is expedient to cast the pile caps horizontally in layers, one on top of another, so that forms used for one layer may be raised and positioned for casting directly on top of the first castings as soon as the concrete has set.

It is the object of the present invention to provide forms for casting concrete pile caps or the like which are simple in construction and easy to strip and set up.

A further object is the provision of a form for casting a rectangular tubular shape with an inner form member which may be easily collapsed for withdrawal when the forms are to be stripped.

A still further object of the invention is a provision in the form of the character described of members for producing rounded outside corners, which members will not interfere with upward stripping of the vertical form walls by which they are carried, and will also leave a slight impression in the casting to aid in the positioning of the forms for successive casting in vertical tiers.

Further objects and advantages of the invention are made apparent in the following specification wherein detailed reference is made to the accompanying drawings.

In the drawings:

Fig. 1 is a central vertical section taken transversely of a form embodying the present invention and illustrating the manner in which it is supported by previously made castings;

Fig. 2 is a fragmentary perspective view illustrating certain details of construction of the form illustrated in Fig. 1;

Fig. 3 is a horizontal sectional view taken on line III—III of Fig. 1;

2

Fig. 4 is a perspective view illustrating one-half of one of the form ends shown in Fig. 3; and

Fig. 5 is an enlarged fragmentary perspective view showing a locking device used for securing the end forms to the main inside and outside form members.

In Fig. 1 a concrete pile cap 10 is shown as having been poured in a form which is set up on top of a layer of previously cast pile caps, portions of which are indicated at 11. The form in which the cap 10 has been poured includes a pair of side walls 12 (see also Fig. 3) which walls are constructed of relatively thin metal plate and serve as forms for the adjacent sides of pile caps which are cast in a group or layer. Being perfectly flat on both surfaces and preferably being sprayed with a lubricant before the concrete is poured, the walls 12, after the poured concrete has set, may be stripped by being raised vertically. As the lower ends of the walls extend below the bottom of the casting, they may be retained, as shown, with a few inches of their edge in place between the caps previously cast so as to guide and support them. In order that the outside corners of the cap will be rounded, each of the side walls 12 is provided with a pair of concave fillets 13 at its upper end, and a similarly shaped, though differently constructed, pair of fillets 14 at its lower end. The upper fillets 13 are bent to a shape which enables them to be securely riveted, welded, or otherwise fastened to the walls 12 in a permanent manner as, being positioned adjacent the top of the form, they do not prevent the form wall from being stripped upwardly from between adjacent castings. They are preferably bent upwardly as indicated at 15 where they are secured to the opposite sides of the members 12 and where they are pierced with holes indicated at 16 which also pass through the members 12 to provide a purchase by means of which the walls may be pulled upwardly. The lower fillets 14, if secured permanently to the side walls, would prevent their being stripped from between the castings, and therefore are formed 45 as separate members which, as shown in Fig. 2, are held in place at their upper edges by clips 17. These clips straddle both of the fillets 14 and are shaped to retain them against the wall 12, the clips 17 being received in notches 18 formed at 50 the upper ends of slots 19 which are somewhat wider than the notches.

When the concrete is poured into the form, it is screeded flush with the top edges of the upper fillets so that due to the double thickness of the 55 metal of which these fillets are bent, a slight

shoulder, shown at 19, is left on the top surface of the casting. As the upper fillets 13 and the lower fillets 14 are of the same dimensions, this shoulder is so positioned that when the forms are stripped upwardly and the lower fillets reset, it supports their lower edges, and when the clips 17 have been inserted in a manner to embrace their upper edges, the form walls may be pressed downwardly and will come to rest on top of the clips; thus the weight of the walls holds the fillets 14 in place while the fillets in turn support the walls at their proper elevation. The reason for the slots 19 being somewhat wider than the notches 18 in which the clips 17 are received is to facilitate stripping of the side walls 12. When these walls are moved vertically upwardly a short distance, say a half inch or so, the clips 17 are released from the notches 18 and as the wider slots 19 pass over the clips, there is no tendency for them to bind or become jammed in the event that the upward movement of the wall is not absolutely vertical at all times. The inner walls of the mould are made up of a substantially square collapsible tube which is formed of four generally right angular members 20. These members are flanged inwardly as indicated at 21 intermediate the corners of the tube and the flanges are connected together by pins 22 which also serve as pivotal supports for sets of links 23 (see also Fig. 3) which are pivoted at their inner ends by pins 24 to the four radial webs of castings 25. The links and castings are spaced throughout the length of the tubular form member and the castings are connected by rods 26, the ends of which are threaded for reception by the threaded interiors of the castings.

The tubular form may be collapsed sufficiently to permit it to be withdrawn from the interior of the pile cap by means of a jack screw 27 at its forward end which is threaded through a nut 28 supported and braced by links 29 connecting it with the tube by the foremost pins 22. This jack screw is connected through a swivel joint 30 with a short rod 31 which is threaded into the foremost of the castings 25 and retained therein by a lock nut 32. Upon turning of the jack screw, which may be accomplished by application of the wrench to its outer squared end, all of the links 23 will be moved to an inclined position and effectively shortened with the result that the form walls at which their outer ends are secured will be drawn inwardly. Were the angular sections 20 of the form each made in a single piece projecting the full distance fully into its respective corner, this inward contraction, particularly where relatively stiff metal must be used to support the weight and pressure of the concrete, would cause the corners to be forced outwardly and would effect binding that would prevent extraction of the tubular form member from the interior of the casting. Consequently, the corners have been constructed in the manner illustrated in Fig. 1 where they are shown as bent on a diagonal indicated at 33 with a central raised or outwardly curved portion 34. A false corner member 35, which is formed of a separate piece of metal and in no way attached to the member 20, is used to complete the corner of the form which was lost in bending it to the plane illustrated at 33. Sufficient clearance is left between the outwardly curved portion 34 and the member 35 so that when the form is drawn inwardly or collapsed, its corners may expand slightly without causing binding, and it may be withdrawn leaving the corner form members 35

in place until after the main portion of the form has been completely removed. These corner members 35 may then easily be loosened and extricated. In setting up the form, the lower corner members 35 are first put in place receiving their support from end members presently to be described. The main rectangular member made up of the four angular members 20 is then inserted and thereafter the upper members 35 are slid into place. With this construction, a collapsible inner form member is made practical and simple to remove. The false corner members 35 may be bent to produce any degree of rounding of the inside corners of the casting, or any other desired shape, and the slight wedge shaped beads 36, which are formed where the false corners join the members 20, may be so small as to be unnoticeable, and do not constitute a disadvantage.

20 The inner form member and the outer walls 10 are held in properly spaced relationship by means of end members which are illustrated at 37 in Fig. 3. These end members, the construction of which is shown in Fig. 4, are formed of a rectangular plate 38 which has its central portion cut out and its inner edges flanged inwardly, as shown at 39, to form a complete rectangle, while its outer edges are flanged as indicated at 40, except at the corners which are rounded as shown at 41 to conform in contour to the fillets 13 and 14 which overlap them. These end wall members receive the inner tubular form member and are embraced on two sides by the outer members 12. They are so constructed that they 25 may be secured either to the inner member or the outer member, and by virtue of this arrangement, a tube of any desired length may be cast in a form of standard dimensions. To determine the length of the tube, the forward end member 30 is secured to the outer walls 12 while the rear end member 37 is secured to the inner members 20. The entire form is therefore in effect telescopic lengthwise so that it may be set up to cast a cap of any length.

45 While the end walls may be secured to the inner and outer form members in any desired manner it is preferred that the form clamp illustrated in Fig. 5 be used. In this figure one of the outer walls 12 is shown as disposed between flanges 40 of two end members which serve as the front walls of adjacent forms. The forward edges of the member 12 as well as the flanges of the end members are perforated as indicated at 42 in Fig. 4 or may in some instances be provided with 50 elongated slots as shown at 43 to accommodate for slight misalignment. The clamp illustrated in Fig. 5 comprises a pin 44 secured to a plate 45. The pin is passed through aligned perforations in the members to be clamped together, and the plate 45 has a lower portion bent around the members to be clamped as indicated at 46 and a tail 47 is bent outwardly from this lower portion for convenience in swinging the clamp about the axis of the pin 44 so that after the pin has been 55 inserted, the clamp may be swung downwardly to embrace the members 40 and the member 12 and retain them together.

Reinforcing steel may be placed in the form but is conventional in its construction and arrangement, and is not here illustrated. When the castings are poured, however, it is necessary that the concrete be vigorously agitated to prevent the occurrence of voids, particularly in the bottom wall wherein the concrete must be poured 60 into a horizontally disposed area, the top of which

is covered by the lower wall of the inner tubular form. To insure that this lower wall is completely poured, it is preferable that the walls of the members 20 on the lower side be provided with small countersunk perforations as indicated at 48 in Figs. 1 and 3 so that when this wall space is completely filled, small portions of the concrete will ooze upwardly through these perforations where they will serve as visible indication that the space beneath them is full. These small perforations, which need not be more than a quarter of an inch in diameter, leave such a small area of roughness on the interior of the casting that it can scarcely be detected, and due to the fact that they are countersunk, the small quantity of concrete which flows through each perforation usually breaks away on contraction of the inner form without danger of filling the indicating perforations, thus making it unnecessary to clean the perforations before each casting operation. All of the form walls, as has previously been stated, are preferably sprayed with a lubricant before casting to facilitate their being stripped and this is particularly desirable of the vertical walls 12 which must be stripped upwardly from between adjacent castings. The bottom wall, however, which is provided by the top surface of a previously cast cap, except in the first instance where the original layer is cast upon foundation planks suitably arranged for that purpose, may be either covered with a layer of paper to prevent adherence of superimposed castings, or may be heavily lubricated for the same purpose.

Having thus described my invention, what I claim and desire to secure by Letters Patent is:

1. Forms for casting rectangular tubular members including rectangular inner form members, means for contracting the walls of said members to permit them to be stripped from the castings, the corners of said inner form members being

bent inwardly to clear the corners of the casting, and separable false corner forms overlying the inwardly bent portions.

2. An inner form for a rectangular tubular member comprising four plates bent to right angles and joined to form a generally rectangular tube, means for bending the walls of said tube inwardly to contract it before stripping it from the shape cast around it, the corners of said tube being bent inwardly to clear the corners of the casting, and false corner forms slidably separable from and overlying the inwardly bent corners.
3. An inner form for a rectangular tubular member comprising four plates bent to right angles and joined to form a generally rectangular tube, means disposed mainly within said tube and engaging said plates at their lines of juncture to draw the walls of the tube inwardly for contracting it before it is stripped from the shape cast around it, the corners of said plate being shaped to clear the corners of the casting, and corner form members slidably separable from and overlying said shaped corners.

ARTHUR E. TROIEL.
